SUPERHEAT REGULATOR

Application filed July 22, 1927. Serial No. 207,712.

Our invention relates to superheat regulators and has for its general object the provision of novel apparatus for desuperheating and reducing the pressure of high pressure 5 superheated steam in plants where it is sometimes advantageous to utilize high pressure steam at reduced pressure and temperature.

A more specific object of the invention is the provision of apparatus comprising a reducing valve and a superheat regulator of the type wherein steam is desuperheated by evaporating water out of contact therewith, in series between the high pressure and low pressure steam supply lines of a steam generating and consuming plant.

Among the still more specific objects of the invention are: to provide apparatus which will accomplish the desired pressure and temperature reduction with the minimum thermal loss; to provide apparatus which will be subjected in part only to the pressure of the low pressure steam supply; and to provide apparatus which will automatically deliver steam to a low pressure 25 steam supply line at uniform temperature.

The nature and more detailed objects of the invention, together with the advantages to be derived from its use, may best be understood from the following description of the invention as applied in a power plant arrangement such as is shown and claimed in the application of Wilbur H. Armacost, Serial No. 207,703, filed July 22nd, 1927, which arrangement we have chosen by way of illustrative example.

In the accompanying drawings:

Fig. 1 is a diagrammatic illustration of the power plant arrangement, and

Fig. 2 is an elevation, partly in section and on an enlarged scale, of the apparatus embodying our invention.

The power plant illustrated is of the type in which a high pressure power generating unit is operated as a base load unit, the exhaust steam from which is utilized in a low pressure unit, the latter also being supplied with additional low pressure steam from an independent source. Under certain load conditions, it is not possible to operate the high pressure unit at capacity. These units

must, however, be operated at substantially constant load, and to provide flexibility in the plant, it is often desirable to cut the high pressure prime mover out of operation and continue the high pressure boilers in operation, utilizing the steam therefrom in the low pressure prime movers.

The principal difficulty in the above mode of operation lies in the fact that the total temperature of the steam coming from the high pressure boilers is above that which can be safely utilized in the low pressure prime movers, and the present invention provides means whereby under such or similar circumstances the high pressure steam can be made use of in apparatus requiring steam at lower pressures and temperatures than those at which the steam is initially supplied.

Referring now to Fig. 1 of the drawings, the numeral 10 indicates a high pressure boiler having a steam and water drum 11 and delivering superheated steam to the high pressure main 12 through the superheater 13. The main 12 is provided with two offtake branches 13 and 14, the former having a control valve 15 located therein and the latter being provided with a control valve 16. The branch main 13 supplies the high pressure turbine 17 which exhausts to conduit 18, the latter being provided with a valve 19 and delivering to the low pressure steam main 20. Steam controlled by valve 22 is supplied by the low pressure main 20 to the low pressure turbine 21.

The branch 14 of the high pressure conduit leads to the reducing valve 23 which delivers steam at low pressure to the regulator, indicated generally at 24. The regulator 24 is placed in communication through valve 25 with the low pressure side of the power plant. A conduit 26 supplies water to the regulator in the arrangement illustrated. We have shown this conduit as leading from the water space of the high pressure drum 11, though this source of water supply need not necessarily come from the high pressure drum as will become apparent hereinafter.

Referring to Fig. 2, in which the regulator is shown in detail, it will be seen that the regulator comprises a base member 27 form-

ing a pair of steam chambers 28 and 29 separated by the partition 30. The tops of chambers 28 and 29 are closed by a common tube sheet 31 in which is mounted a plurality of U-shaped tubes 32 so arranged that one end of each tube is in communication with chamber 28 while its other end is in communication with chamber 29. The tube bundle 32 is enclosed in a housing 33 having a suitable cover plate 34 and forming a closed chamber 35 which is placed in constant communication with the chamber 28 by means of the conduit 36.

Chamber 29 is placed in communication with the low pressure side of the plant through valve 25 and conduit 37, the latter having placed therein a thermostatic element 38 which controls the valve 39 located in conduit 26 connecting the chamber 35 with the drum 11. Adjacent to the upper end of chamber 35, a ball float 40 is provided which controls, through the connection 41, a stop valve 42 placed in conduit between valve 39 and drum 11. The ball float 40 is housed in a casting forming a chamber 43, the latter being in communication with the chamber 35 through connections 44 and 45.

Chamber 35 is preferably provided with a suitable safety valve 46 and chamber 28 is also provided with a suitable relief valve 47.

The operation of the power plant illustrated is as follows: When the plant is operating under a load greater than that which can be supplied by either the high or low pressure units alone, steam generated in the high pressure boiler 10 passes through turbine 17 from which it is exhausted to the low pressure side of the plant in communication with the low pressure main 20 (the latter being supplied with low pressure steam from boilers not shown), and this low pressure steam is utilized to operate turbine 21. With the plant operating in this manner, valves 16 and 25 are closed and the regulator 24 is not used.

When the load on the plant drops to a point where this combined output of turbines 17 and 21 is greater than required, the former is cut out of service, but as the regulation of the load on boiler 10 is much more difficult than on the low pressure boilers, this boiler is kept running under its normal load and the steam therefrom is utilized in the low pressure turbine, the total amount of low pressure steam being reduced by cutting one or more of the low pressure boilers out of service. When the plant is operated in this manner, valves 15 and 19 are closed, thereby cutting off the turbine 17. Valves 16 and 25 are opened and steam delivered from the boiler 10 passes through the reducing valve 23 and is delivered at low pressure to the chamber 28. From the latter it passes through the tubes 32 to the chamber 29 and from the latter through the connection 37

and valve 25 to the low pressure turbine 21.

The steam passing through the tubes 32 is desuperheated by giving up a portion of its heat to water supplied to the chamber 35 through the conduit 26, and the amount of desuperheating which takes place obviously varies in accordance with the amount of water in chamber 35.

As the highest rate of heat transfer may be obtained from the evaporation of water, it is highly desirable that the water supplied to chamber 35 be at a temperature at or near that at which it will evaporate, and for this reason I prefer to connect the conduit 26 with the drum 11 although other sources of heated water, such as the boiler feed line in case a preheater is used, may be utilized.

Steam formed in chamber 35 by the evaporation of water therein is conducted by means of the conduit 36 to the chamber 28, where it mixes with the superheated steam at reduced pressure and passes through the tubes 32, reducing to some extent the amount of desuperheating which must be accomplished in these tubes. The water level in chamber 35 is maintained at the proper height to give the final temperature desired to the steam leaving the regulator by the regulation of the valve 39, which is responsive to the thermostatic element 38 subject to the influence of the steam passing from the regulator.

The float 40 is provided to operate the emergency shutoff valve 42 in case the valve 39 fails to function properly, thus preventing the water in chamber 35 rising and passing over through conduit 36 into the steam chamber 28, from which it would be carried into the low pressure mains with serious results to the low pressure turbines.

The invention has been described as applied in a specific form of power plant design in order to illustrate the several specific advantages which use of the invention makes available. It will be apparent, however, to those skilled in the art that the invention is susceptible to use in many other arrangements, in some of which all of the advantages hereinbefore pointed out may be availed of and in others of which some of the advantages inherent in the invention may be availed of to the exclusion of others.

From the foregoing it will be understood that the invention is not limited to the specific arrangement shown by way of example, but embraces all such variations as may fall within the scope of the appended claims.

We claim:

1. In apparatus of the class described, a high pressure superheated steam conduit, a low pressure steam conduit, a steam connection between said conduits comprising a pressure reducing valve and a superheat regulator located in series in the connection, said regulator comprising a plurality of

- tubular elements forming part of said connection, a casing forming a closed chamber around said elements, means for supplying water under pressure to said chamber, and a conduit placing said chamber in communication with one of said first named conduits, whereby said chamber is maintained under a pressure at least as high as the pressure in the low pressure conduit. 5
2. In apparatus of the class described, a high pressure superheated steam conduit, a low pressure steam conduit, a steam connection between said conduits comprising a pressure reducing valve and a superheat regulator located in said connection, said regulator comprising inlet and outlet chambers, a plurality of tubular elements connecting said chambers, a casing forming a closed chamber around said elements, means for supplying water to said chamber, means for maintaining the water level in said chamber below a predetermined level, whereby a steam space is maintained in the upper portion of the chamber, and a conduit connecting said steam space with one of said first named conduits whereby the water in said casing is maintained under a pressure at least as high as the pressure in the low pressure conduit. 10
3. In apparatus of the class described, a high pressure superheated steam conduit, a low pressure steam conduit, a connection between said conduits comprising a pressure reducing valve and a superheat regulator located in series in said connection, said regulator comprising a plurality of tubular elements forming part of the connection, a casing forming a closed chamber around said elements, means for supplying heated water under pressure to said chamber, means for controlling the water level in said chamber to provide a steam space in the upper portion thereof, and a conduit for conveying from said chamber steam generated therein, the discharge end of said conduit being connected to a steam space under pressure, whereby the water in said casing is maintained under pressure and the steam generated therein is rendered available for useful work. 15
4. In a power plant, a high pressure superheated steam supply line, a low pressure steam supply line, a conduit connecting the high pressure and low pressure lines, a pressure reducing valve and a superheat regulator of the type wherein steam is desuperheated by evaporating water out of contact therewith located in series in said conduit, a conduit for supplying water to said regulator, and a conduit for conveying steam generated by the evaporation of water in said regulator to a point in communication with one of said steam lines. 20
5. In a power plant, a high pressure superheated steam supply line, a low pressure steam supply line, a conduit connecting the high pressure and low pressure lines, a pressure reducing valve and a superheat regulator of the type wherein steam is desuperheated by evaporating water out of contact therewith located in series in said conduit, a conduit for supplying water to said regulator, and a conduit for conveying steam generated by the evaporation of water in said regulator to a point in communication with one of said steam lines. 25
6. In a power plant, a high pressure superheated steam supply line, a low pressure steam supply line, a conduit connecting the high pressure and low pressure lines, a pressure reducing valve and a superheat regulator of the type wherein steam is desuperheated by evaporating water out of contact therewith located in series in said conduit, a conduit for supplying water to said regulator, and means for conducting steam generated by the evaporation of water in said regulator to a zone of pressure from which said steam is taken to do useful work, whereby the water is maintained under pressure in said regulator and the steam generated therein is usefully employed. 30
7. In apparatus of the class described, a high pressure steam inlet conduit, a low pressure steam delivery conduit, a pressure reducing valve located in said inlet conduit, a superheat regulator located between said reducing valve and said delivery conduit, said regulator comprising inlet and outlet chambers, a plurality of tubular elements connecting said chambers, a casing forming a closed chamber around said elements, means for supplying heated water to said chamber, and means responsive to the temperature of the steam in one of said conduits for maintaining a water level in said last named chamber below the top thereof. 35
8. In apparatus of the class described, a high pressure steam inlet conduit, a low pressure steam delivery conduit, a pressure reducing valve located in said inlet conduit, a superheat regulator located between said reducing valve and said delivery conduit, said regulator comprising inlet and outlet chambers, a plurality of tubular elements connecting said chambers, a casing forming a closed chamber around said elements, means for supplying heated water to said chamber, and means responsive to the temperature of steam passing through said delivery conduit for maintaining a water level in said last named chamber below the top thereof. 40
9. In apparatus of the class described, a high pressure steam inlet conduit, a low pressure steam delivery conduit, a pressure reducing valve located in said inlet conduit, a superheat regulator located between said reducing valve and said delivery conduit, said regulator comprising inlet and outlet chambers, a plurality of tubular elements connecting said chambers, a casing forming a closed chamber around said elements, means for supplying heated water to said chamber, and means responsive to the temperature of steam passing through said delivery conduit for maintaining a water level in said last named chamber below the top thereof. 45
10. In apparatus of the class described, a high pressure steam inlet conduit, a low pressure steam delivery conduit, a pressure reducing valve located in said inlet conduit, a superheat regulator located between said reducing valve and said delivery conduit, said regulator comprising inlet and outlet chambers, a plurality of tubular elements connecting said chambers, a casing forming a closed chamber around said elements, means for supplying heated water to said chamber, and means responsive to the temperature of steam passing through said delivery conduit for maintaining a water level in said last named chamber below the top thereof. 50

- ing said chambers, a casing forming a closed chamber around said elements, means for supplying heated water to said chamber, means responsive to the temperature of the steam in one of said conduits for controlling the water level in said chamber, and a conduit connecting said last named chamber above the water level therein with said inlet chamber. 10. In apparatus of the class described, a high pressure steam inlet conduit, a low pressure steam delivery conduit, a pressure reducing valve located in said inlet conduit, a superheat regulator located between said reducing valve and said delivery conduit, said regulator comprising inlet and outlet chambers, a plurality of tubular elements connecting said chambers, a casing forming a closed chamber around said elements, means for supplying heated water to said chamber, means responsive to the temperature of steam passing through said delivery conduit for controlling the water level in said chamber, and a conduit connecting said last named chamber above the water level therein with said inlet chamber. 11. A superheat regulator comprising means forming an inlet chamber and an outlet chamber, a plurality of tubular elements connecting said chambers, a casing forming a closed chamber around said elements, means for admitting water to said last named chamber, means responsive to the temperature of steam leaving the regulator for controlling the water level in said last named chamber, and a conduit connecting said last named chamber above the water level therein with said inlet chamber. 12. A superheat regulator comprising means forming an inlet chamber and an outlet chamber, a plurality of tubular elements connecting said chambers, a casing forming a closed chamber around said elements, a conduit supplying water to said last named chamber, a thermostatically controlled valve located in said conduit, said valve being responsive to the temperature of steam leaving the regulator, a stop valve in said conduit, float controlled means for closing said last named valve when the water level in said last named chamber reaches a predetermined height, and a conduit connecting a point in said last named chamber above said predetermined height with said inlet chamber. 13. In a power plant, a high pressure superheated steam supply, a low pressure steam supply, means for reducing the pressure and temperature of steam passing from said high pressure supply to said low pressure supply, said means comprising a pressure reducing valve receiving high pressure steam, a superheat regulator of the type wherein steam is desuperheated by evaporating water out of contact therewith, said regulator receiving steam from said reducing valve and delivering it to said low pressure supply, and means for delivering steam generated by the evaporation of water within said regulator to the low pressure steam supply. 14. In a power plant, a high pressure superheated steam supply, a low pressure steam supply, means for reducing the pressure and temperature of steam passing from said high pressure supply to said low pressure supply, said means comprising a pressure reducing valve receiving high pressure steam, a superheat regulator of the type wherein steam is desuperheated by evaporating water out of contact therewith, said regulator receiving steam from said reducing valve and delivering it to said low pressure supply, and means for delivering the steam generated by the evaporation of water within said regulator to the steam inlet end of said regulator. RALPH M. SWARTZ. SVEND M. JORGENSEN.
